UNITED STATES PATENT OFFICE

HARRY LEBERMAN, OF NEW YORK, N. Y., ASSIGNOR TO GROOVE LOCK CO. INC., OF NEW YORK, N. Y., A CORPORATION OF NEW YORK

FASTENING DEVICE FOR BAG HANDLES AND THE LIKE

Application filed July 10, 1928. Serial No. 291,674.

This invention relates to fastening devices and particularly to the type set forth in United States Letters Patent No. 1,623,610 dated April 5, 1927 to Anton Zeindlhofer, Sr.

5 The improvement thereover consists in the special arrangement of the bag frames, one of which is provided with a rail superposed on the frame and spaced therefrom which rail is provided with a slideable fastening member, and the other part of which frame is provided with an abutment member adapted to be engaged by the fastening member.

10 The novel structure is very simple, inexpensive to make, and creates an appearance which is ornamental. The parts are so disposed that apparently the least change is made over the ordinary bag frame, which simplicity makes such a fastening device desirable by fastidious customers.

15 My invention consists in a fastening device comprising two cooperating parts so disposed on the bag frames as to permit the two frames to be readily secured together one of these parts consisting of a slide and the other part of an abutment, the abutment being adapted to be engaged by the slide. The slide operates on a rail spaced from one of the frames, which rail embraces the abutment when the frames contact in closed position.

20 The invention consists further of certain features which will be more fully described hereinafter and finally pointed out in the claims.

In the accompanying drawings,

25 Figure 1 is a perspective view of an embodiment of my invention,

Fig. 2 is an enlarged view,

Fig. 3 a transverse section, and

Fig. 4 a detail sectional view.

30 Similar characters of reference indicate corresponding parts.

Referring to the drawings and particularly to Figures 1 and 2, the bag frames 10 and 11 are hinged at 12 in the usual manner. Suitable means 13 are provided to enable the bag body to be fastened to the frames, and one of the frames is provided with the usual eyelets 14 for the handle.

35 As far as described the parts are old. To one of the frames 11, a rail 15 is secured, 50 which rail 15 is spaced from the wall of the

frame. Intermediate the outer wall 16 of the frame 11 and the inner wall 17 of the rail 15, spacing members 18 are provided suitably spaced longitudinally and in one embodiment five of such members 18 are provided, though more or less may be employed. The rail is not spaced at the sides of the frame but is contiguous thereto. The rail could be contiguous to the upper surface of the frame to a greater extent than in the embodiment, 55 as long as sufficient space is left for the path of movement of the underbent part of the fastening member about to be described.

The rail is embraced by the fastening member 20 which consists of a slideable carriage 60 with walls 22 almost entirely surrounding the rail so as to be secured in a manner that it cannot fall off. The member 20 is provided with a small enlargement 23 serving as a convenient hand grip. The walls 22 extend 70 so far around the rail, that a part of these walls 22 encounters one of the spacing members 18, at one end of the path of the movement of the slideable member 20, and encounters another of these spacing members at 75 the other end of the path of movement of the slideable member 20.

To the other frame 10, is secured an abutment member 25 having a length less than the length of the path of movement of the 80 slideable member 20.

The thickness of this abutment is such that when the straight inner confronting faces of the frames are in intimate contact, the abutment may be embraced by the inner 85 end of the overbent part on one wall of the slideable member 20, and when so embraced in the closed position the abutment is in a position completely within or underneath the rail. As the abutment moves into the closing position, there is a slight frictional contact between the top edge of the abutment and the underneath surface of the rail which frictional action must be overcome when closing the frame, and when opening the same. 90 The resistance to this frictional action serves to hold the frames momentarily closed when the fastening member is being disengaged, so that the bag does not open too quickly. This frictional engagement is not essential. 95

In the embodiment, when the frames are in open position the slidable member 20 is at one end of its path of movement against one spacing member. The frame having the abutment is closed by pressing the abutment inwardly underneath the rail so that the slidable member can be moved along the rail to engage over and to embrace the abutment. In this manner the frames are fastened, but to secure this fastening action the slidable member is moved along the rail and over the abutment until, to the end of the path of its movement, it abuts against the other spacing member. Even then the abutment extends beyond this path of movement, but this is largely for ornamental or symmetrical reasons.

The outer wall 26 of the abutment holding frame is spaced from the underneath wall 17 of the rail about the distance equal to the height of the abutment.

To unfasten the frames for opening movement, the slidable member is moved beyond the abutment, and as soon as this takes place, the frames can be separated.

From the foregoing description taken in connection with an inspection of the drawing, it will be understood that the slidable or fastening member 20 is movable along the rail between two spacing members 18; and also that when the frame sections are closed with their straight inner faces in intimate contact (as shown in Fig. 3), the top end of the abutment 25 will be frictionally engaged with the underneath surface of the wall 17 of the rail so that the wall portion of the fastening member 20, which slidably fits the underneath surface of said wall 17, can be frictionally engaged at its inner end upon the outer bearing face of the abutment 25, whereby rigidly to secure the frame sections in closed position.

I have described an embodiment of my invention but it is clear that changes may be made therein without departing from the spirit of my invention as defined in the appended claims.

I claim as new.

1. A fastening device for bag frames comprising two frame sections having flat inner faces to fit throughout their extents in flat facewise contact, a rail surmounting the top of one section and overhanging the flat face thereof, the overhanging part of the rail having an underneath bearing face forming a space between it and the top of the second section, an upstanding rib at the inner top corner of the second section, the inner face of said rib being flat and coplanar with the inner flat face of the second section to fit therewith in flat facewise contact against the inner face of the first section, the top edge of said rib comprising a cam working edge to contact the underneath bearing face of said overhanging part and thus secure a prelim-

inary fastening action, a fastening element slidable along said rail for engaging said rib, the part of the fastening element for engaging said rib comprising an arm having sliding contact with the underneath bearing face of said overhanging part, the inner reach of said arm being such that its free inner edge affords a cam working edge to engage the outer face of said rib and thereby to complete the fastening action, with the top of said rib engaging the underneath face of the bearing part and with the inner coplanar faces of said rib and second section in flatwise contact throughout their extents against the flat inner face of the first section.

2. A fastening device for bag frames comprising two frame sections having flat inner faces to fit throughout their extents in flat facewise contact, a rail separate from said sections surmounting the top of one section to overhang the top of the second section, spacers in the form of pins connecting said rail to its section, the overhanging part of said rail having an underneath bearing face forming a space between it and the top of the second section, an upstanding rib at the inner top corner of the second section and having an inner face which is flat and coplanar with the inner face of the second section to fit therewith in flat facewise contact against the inner flat face of the first section and within said space, the top edge of said rib comprising a cam working edge to contact the underneath bearing face of said rail and thus secure a preliminary fastening action, a fastening element slidable along said rail for engaging said rib, the part of the fastening element for engaging said rib comprising an arm in sliding engagement with said underneath bearing face and having a free inner edge which serves as a cam working edge to engage the outer face of said rib and thereby to complete the fastening action, with the inner coplanar faces of said rib and outer section pressed facewise throughout their extents against the flat inner face of the first section and within the compass of said surmounting rail.

In testimony that I claim the foregoing as my invention, and have signed my name here-

HARRY LEBERMAN.
